United States Patent Office.

GEORGE H. DEUELL, OF BROOKLYN, NEW YORK.

Design No. 3,538, dated June 15, 1869.

DESIGN FOR A LANTERN.

The Schedule referred to in these Letters Patent and making part of the same.

To all whom it may concern:

Be it known that I, GEORGE H. DEUELL, of the city of Brooklyn, in the county of Kings, and State of New York, have originated and designed a new Emblematic Lantern, of which the following is a full, clear, and exact description, reference being had to the accompanying drawings, making part of this specification.

This invention relates to a new and original design for an emblematic lantern.

The design consists in making a lantern in the shape of a barrel, which would be emblematic of the calling of one who deals in wines, beer, &c.

The accompanying drawing represents a perspective view of my emblematic lantern, made in accordance with my design.

The frame, or ribs A, of this lantern, may be made of brass or iron. I prefer to make them of brass, with gilded surface.

The hoops B will be made of the same material, but, by way of contrast, will be japanned black.

The staves C are made of glass, properly secured to the ribs, or frame, as in ordinary lanterns.

It will be observed, that in the direction of their length the staves C are divided into three separate pieces. These pieces are colored, alternately, red, white, and blue.

The heads D are also of glass, colored a deep red or crimson.

In one of the heads, I construct a door, or man-hole, F, so that a boy may enter into the lantern and clean it out from time to time.

In the upper side of the bilge, I construct a ventilator, or smoke-hole, E, of such shape and dimensions as will represent the bung of a barrel, and through an opening in the lower side of the bilge is introduced a gas-jet, for the purpose of illuminating the lantern.

The lantern thus complete is secured, in any manner desirable, in front of the wine-store for which it is intended to act as a sign.

What I claim as my invention, and desire to secure by Letters Patent, is—

A new and original design for an emblematic lantern, in the shape of a barrel, the glass staves of which are colored, alternately, white, red, and blue, and the glass heads colored crimson, or other color, with door so constructed as to admit a boy for the purpose of cleansing, all as set forth.

GEO. H. DEUELL.
